J. CROMBIE

BOILER TURNING CRADLE

Filed Dec. 30, 1921

Inventor.

James Crombie,
By Geo. A. Hutchinson

Attorney.

UNITED STATES PATENT OFFICE.

JAMES CROMBIE, OF ST. LOUIS, MISSOURI.

BOILER-TURNING CRADLE.

Application filed December 30, 1921. Serial No. 525,951.

To all whom it may concern:

Be it known that I, JAMES CROMBIE, a citizen of the United States, residing at St. Louis, in the county of St. Louis City and State of Missouri, have invented certain new and useful Improvements in Boiler-Turning Cradles, of which the following is a full, clear, and exact specification.

This invention relates to boiler turning cradles, and particularly to means for controlling the rotation of boiler shells on the cradles to bring successive points into proper alignment for boring or reaming rivet holes therein.

The code of the American Society of Mechanical Engineers requires that all boiler shells be drilled or holes punched one quarter inch ($\frac{1}{4}$ ") small and reamed to size. This drilling or reaming is done under a drill press, or wall radial drill, the boiler being set on the rollers of a cradle and rotated by means of a screw jack, chain hoist, or in more up-to-date shops with a belt and pulley geared to the roller shaft. In each of these cases, it is necessary to provide an extra workman or helper to operate the turning device, that is, to turn the screw jack, actuating the chain hoist, or shift the belt from the loose pulley to the tight pulley and vice versa, in order to rotate the pulley shell to bring the next hole in proper position for drilling. This means great loss of time as the drill operator after finishing one hole has to sign to the helper to move the boiler to the next hole. The helper down on the floor cannot see how far he has rotated the boiler shell and must depend on the sign given him by the drill operator, so that sometimes he turns the boiler too far, while at other times not far enough.

The present invention is designed to eliminate this loss of time and dispenses with the helper entirely. To this end, the cradle is operated by a reversible electric motor having a magnetic control panel with which as many push button or switch stations as are necessary are connected so that one of said stations may be always in easy reach of the drill operator, no matter what size of boiler shell is being worked upon. These switch stations are preferably placed at intervals along the arm of the drill and project downwardly therefrom so that the drill operator can readily put his hand on

them from either side of the drill. Each switch station preferably consists of two push buttons for operating the motor in opposite directions, the boiler being only rotated as long as one of the buttons is pressed, so that when said buttons are released the motor stops, and the boiler ceases to rotate. The operator being directly in front and looking down upon the hole can quickly center the next hole in line with the drill and work in either direction.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:

Figure 1 is an elevation of a drill press and boiler turning cradle having the present invention applied thereto.

Figure 2 is a sectional view on the line II—II of Figure 1 showing more particularly the actuating means for the active rollers of the cradle.

The drill press 1 is suitably mounted on a wall or other support 2 and has a horizontally extending arm 5 adapted to be adjusted vertically to accommodate different sizes of boiler shells 12. The drill or reamer 4 is mounted on a carriage 3 which is adjustable along the arm 5 to bring said drill or reamer directly over the axis of the boiler shell. Said drill or reamer is rotated by means of an electric motor 6 geared at 7 to a vertical shaft 8, in turn geared at 9 to a horizontal shaft 10 running along the arm 5, the drill or reamer itself being geared at 11 to said horizontal shaft 10.

The cradle on which the boiler shell 12 is supported and rotated consists of a plurality of angle bars 17 in which roller shafts 15 and 16 are suitably journaled. The shaft 15 may be mounted in fixed journals and carry a worm gear 19 meshing with a worm 20 on an operating shaft 21, suitably journaled at 22 and carrying a gear 23 meshing with a gear 24 on the armature shaft of a reversible electric motor 25. The rollers 13 on said shaft 15 are, therefore, the active rollers of the turn-table, and the rotation thereof in

one direction or the other by the motor 25 will cause the boiler shell 12 to rotate in the corresponding direction.

The shaft 16 carries rollers 14 which idly support the boiler shell 12, and a plurality of spaced journal notches 18 are provided in the bars 17 for adjusting said shaft at different distances from the active roller shaft 15 so as to adapt the cradle to accommodate different sizes of boiler shells. The drill operator may sit upon the top of the boiler shell or stand on a platform 31 erected at one side of said boiler shell. In either position, he is in easy reach of the hand lever 30 for raising and lowering the drill or reamer 4, and also in reach of one or more of a series of push button or switch stations 29 depending at intervals from the drill arm 5 and adapted to control the operation of the motor 25 through a conductor cord 28 leading to a magnetic control panel 27, in turn connected to the motor by a conductor cord 26. The cradle may thus be readily controlled by the drill operator, thereby expediting his work and also saving the ex-

pense of a separate workman which was necessary for operating said cradle, in the prior mechanisms hereinbefore mentioned.

I claim:

1. In combination, a boiler turning cradle 30 for a drill press comprising a set of supporting rolls two of which are connected to rotate as a pair, a reversible electric motor connected to said pair of rolls to positively rotate the same in either direction, and controls for said motor located on the drill press 35 convenient to the drill controlling mechanism.

2. In combination, a boiler turning cradle 40 for a drill press comprising a set of supporting rolls two of which are connected to rotate as a pair, a reversible electric motor connected to said pair of rolls to positively rotate the same in either direction, and controls for said motor located on the drill press 45 at spaced intervals convenient to different positions of the drill controlling mechanism.

In testimony whereof I have signed my name to this specification.

JAMES CROMBIE.
